United States Patent Office

Des. 208,194
Patented Aug. 1, 1967

208,194

RADIO CONTROL KNOB OR SIMILAR ARTICLE

Melvin H. Boldt, Glenview, Ill., assignor to Zenith Radio Corporation, Chicago, Ill., a corporation of Delaware

Filed Oct. 15, 1965, Ser. No. 87,503

Term of patent 14 years

(Cl. D26—13)

FIG. 1

FIG. 4

FIG. 2

FIG. 3

FIG. 5

FIGURE 1 is a perspective view of a radio control knob or similar article, showing my new design;

FIGURE 2 is a front elevational view thereof;

FIGURE 3 is a side elevational view thereof;

FIGURE 4 is a sectional view as seen from line 4—4 of FIGURE 2; and

FIGURE 5 is a sectional view as seen from line 5—5 of FIGURE 2.

The dominant features of my design reside in those portions of the drawing shown by means of full lines.

I claim:

The ornamental design for a radio control knob or similar article, substantially as shown and described.
